HEADREST CUSHION

Roy Requa, 5801 N. Federal Blvd., Denver, Colo.

Filed Aug. 28, 1961, Ser. No. 66,511

Term of patent 14 years

(Cl. D15—8)

I claim:

The ornamental design for a headrest cushion, substantially as shown.
